UNITED STATES PATENT OFFICE.

WALTER A. KRENTLER, OF DETROIT, MICHIGAN, ASSIGNOR TO KRENTLER-ARNOLD
HINGE LAST COMPANY, OF DETROIT, MICHIGAN, A CORPORATION OF MICHIGAN.

TWO-PART LAST AND METHOD OF MAKING SAME.

Application filed September 4, 1926. Serial No. 133,602.

My present invention is a novel and improved construction for shoe lasts wherein the forepart and heel part are relatively movable to facilitate withdrawing the same from a shoe, as well as to enable such a last to be more readily fitted to a shoe for re-lasting.

My invention also comprises a novel method of constructing and assembling such last parts and the connecting hinge members.

In the manufacture of boots and shoes it is of great importance to have a last which can be quickly and easily withdrawn from the shoe after the shoe has been built thereon, without straining, distorting, or otherwise damaging the completed shoe. For this purpose it is necessary that the last may be "shortened" before or as it is withdrawn from the shoe. Heretofore such "shortening" of shoe lasts has been effected by pivotal or sliding constructions, and the location of the uniting link, links, members or the connecting pins or pivots, as well as the position and shape of the lines of cut dividing the forepart and heel part. In other prior last constructions entire sections were removed to facilitate the withdrawing from the shoe. In my present invention I have discovered a last construction and method of making same which will permit of a positive lengthwise shortening of the last parts in addition to, and independent of, the swinging of the same on the uniting member or pivot points, and a method of so forming and constructing the last parts and connecting members as to still hold the forepart and heel part firmly and rigidly united when in extended position. Thus, by my present invention I am enabled to produce a two part last construction which automatically effects a positive longitudinal shortening of the last parts, from heel to toe, by and during the mere action of relative movement between the heel part and forepart, thus instantly and positively "loosening up" the last within the shoe and greatly facilitating its removal therefrom. This swinging feature also facilitates the utilization of this construction in fitting a last into a shoe for re-lasting purposes, thus rendering my present improved last as peculiarly fitted

both for a "first" last and as a "second" last for re-lasting, shoe treeing, and the like.

In carrying out my present invention I

prefer to employ a connecting union or link member substantially like that of my prior and copending application Ser. No. 745,364 55 wherein I have illustrated a convenient tension member, well known in the art as an "accordion" spring, which acts to hold the forepart and heel part together. Also I may prefer to utilize, and I herein show, a link 60 construction together with a filling or side pressure member known as a "Dutchman", more fully illustrated and described in my copending application 74,166, although it will be appreciated that other connecting 65 members can be utilized to advantage.

I have discovered that, by providing a recess or space in the last members appropriately positioned to permit a substantial longitudinal shortening of the last members 70 during the relative movement of heel part and forepart, while constructing the faces of the last members to automatically straighten out or lengthen the entire last structure when the last parts are completely 75 extended, or the securing of a firm, rigid construction while yet obtaining an improved shortening of the last in addition to the shortening secured by the pivotal action of the two parts. This feature I may secure by 80 forming either the socket or knuckle parts on slightly non-concentric arcs or, indeed, in forming one as the socket portion on two slightly non-concentric arcs and the knuckle portion in a single arc. Thus, during the 85 collapsing action, the knuckle can readily fit, slide, work or turn into a recess accorded by such construction, while it will turn out of such recess and into full lengthened position on completing of the pivotal action, thereby 90 lengthening the last to its full proportions. Furthermore I secure these desirable results automatically, and with a strong, simple construction, and the member, union, link, or connecting device, acting under tension so 95 as to hold the last parts at all times in firm contact.

Further features, novel combinations, and important advantages will be pointed out and claimed.

Referring to the drawings illustrating a preferred embodiment of my invention,

Fig. 1 is a side view, partly in cross section, illustrating my invention and the method of

making same, showing the last in extended position;

Fig. 2 is a fragmentary view, also in cross section, illustrating my present invention in "collapsed" position, and

Fig. 3 is a fragmentary cross sectional view on the line 3—3 of Fig. 1.

As shown in the drawings, I form my last having a forepart 1 and heel portion 2 of any size, shape, style or contour. These parts are divided on the line of cut from the last bottom at 5 to abutting shoulders or faces 6 on the forepart and 7 on the heel part, and thence with a short, preferably straight, section 8 on the forepart and 9 on the heel part, which may be broken when the parts are sawed, as explained in the Carl Patent No. 969,244. From this section forwardly I form the line of cut with complementary knuckle 20 and socket faces. As herein illustrated, the knuckle section is on the heel part, though this may be reversed, if desired. This line of cut on the heel part is indicated at 10, and is substantially circular. On the complementary socket faces, however, here shown as the forepart, I form at 12 and 14 two curved sections, each capable of fitting snugly on the knuckle portion 10, but on non-concentric arcs which will merge together at substantially the middle portion of the socket face, as indicated at 15, so as to give a smooth bearing between the parts as the last members are moved from collapsed to extended position or vice versa. On the heel part I may carry the knuckle member arc to a considerable extent on its line of cut to a position substantially shown at 18 and thence outward along the face 19. On the forepart I carry the line of cut substantially as shown at 20 to thus provide ample space between the faces 19 and 20 to permit collapsing of the last, as illustrated in Fig. 2.

With the lines of division formed as above outlined, I then cut a complementary recess, 45 as by a saw curve 21 in the forepart, and 22 in the heel part, to receive the connecting link or member. Such a member may be an "accordion" spring tension link 25, as more fully described and explained in my said co-pending application. This link will also be bored to receive the rivets or pins 26 and 27 and preferably, also, I supply a bearing member or "Dutchman" 28 adapted to engage the adjacent faces of the knuckle and socket across the lines of cut—as best shown in Fig. 3—and thus serve to hold the parts in correct alignment during the collapsing and extending action. The tension of the member 25 holds the last parts at all times in firm 55 contact, thus forcing the last parts together and effecting the longitudinal shortening as the faces move into the recess accorded by the non-concentric faces, while permitting lengthening as the members move out of

same, and also automatically compensating 65 for wear.

It will thus be seen that my present invention provides a simple, strong, novel, and efficient construction, including means affording a positive longitudinal shortening 70 through the lengthwise portions of the last itself, and automatically permitting the last to thus shorten, as well as to extend the same to full position, all during the mere moving action of the fore part and heel part relatively with each other. I believe it to be a distinct novelty in this art to provide means affording positive longitudinal shortening action in a two part last by providing a recess or space into which the complementary 75 contacting faces of forepart and heel part may be moved, and I wish to claim the same herein broadly. I also am advised that it is a distinct novelty to provide both a shortening from swinging on a pivot and a positive 80 shortening lengthwise in addition to, or independent of, the swinging of last parts accorded by the pivotal action, and therefore I wish to claim this feature broadly. I also consider it an important novelty to have complementary last engaging faces on heel part 85 and forepart constructed and arranged in non-concentric arcs which merge together, facilitating the shortening and pivotal action, and I claim these features broadly 90 therein.

A last made as described herein accomplishes two features instead of one, which I claim broadly. In the one, the heel part shortens from pivot center only, said center being located at, or below, the center of back of heel. In my new invention I accomplish, in addition, longitudinal shortening by cutting away the socket from a different radius, permitting the heel part to drop from the pintle center into this additional space when last is collapsed, thereby having two shortenings instead of one.

Having thus described my invention, what I claim as new is:

1. A last having a forepart and heel part, means connecting said parts, and complementary faces provided with recesses on their contacting face portions, arranged so as to permit relative movement whereby one part may move into the recess of the other part and effect a positive longitudinal shortening action during the relative movement of the last parts.

2. A last having a forepart and heel part relatively movable, means connecting said parts, said parts having cooperating knuckle and socket portions with complementary portions formed on non-concentric arcs.

3. A last having a forepart and heel part relatively movable, means connecting said parts, said parts having cooperating knuckle and socket portions with complementary por-

tions formed on non-concentric arcs in combination with a connecting means exerting tightening tension on the last parts.

4. A last having a forepart and heel part, means connecting said parts, one of said parts being provided with an extended knuckle and the other with a complemental socket portion, said knuckle portion being formed on one arc and the socket portion having a part non-concentric with said knuckle portion whereby a space or recess is provided into which the knuckle portion will drop during relative movement when collapsing, and out of which the knuckle portion will be moved during extending action.

5. A last having a forepart and heel part, means connecting said parts, one of said parts being provided with an extended knuckle and the other with a complemental socket portion, said knuckle portion being formed on one arc and the socket portion

having a part non-concentric with said knuckle portion whereby a space or recess is provided into which the knuckle portion will drop during relative movement when collapsing, and out of which the knuckle portion will be moved during extending action in combination with connecting means having a yielding structure.

6. The improved method in the art of manufacturing shoe lasts having a forepart and heel part arranged for relative movement on each other, which consists in forming one part with a projecting knuckle portion and the other part with a complemental socket portion, said socket having a part non-concentric with the knuckle to provide a space or recess into which the knuckle may drop during collapsing.

In testimony whereof, I have signed my name to this specification.

WALTER A. KRENTLER.
